ATION OF VIRGINIA.

PAPER-GUARD FOR FOLDING MECHANISM.

1,271,644.

Specification of Letters Patent.

Patented July 9, 1918.

Application filed June 16, 1913. Serial No. 773,915.

To all whom it may concern:

Be it known that I, HENRY A. WISE WOOD, a citizen of the United States, residing at New York, in the county of New York and 5 State of New York, have invented a new and useful Paper-Guard for Folding Mechanism, of which the following is a specification.

This invention relates to the folding rolls 10 forming a part of the folding mechanism used ordinarily on folders of web printing presses.

The principal objects of the invention are to provide means for preventing any contact 15 of the paper on the folding rolls and especially to prevent the off one of the two rolls, that is the one toward which the paper is being carried by the cylinder, from engaging the edge of the incoming sheet so as to 20 carry it down and thus wrinkle it.

The invention also involves improvements in details of construction as will appear hereinafter.

Reference is to be had to the accompanying drawings in which,

Figure 1 is an end elevation of a part of a folding mechanism showing the folding rolls and some other parts in transverse section and showing one form of this invention 30 applied thereto;

Fig. 2 is a plan of one of the folding rolls and guards therefor; and

Fig. 3 is a sectional view of the same on the line 3—3 of Fig. 2.

The invention is shown as applied to a folding mechanism comprising a folding cylinder 1, a cutting cylinder 2 and folding rolls 3 and 4. The folding cylinder is shown as provided with the usual folding blade 5 40 and paper forwarding pins 6.

As ordinarily constructed, the paper is carried around the folding cylinder until it reaches the position in which it is cut. Then it is tucked into the nip of the folding rolls 45 3 and 4 by the folding blade. Then it is folded and forwarded by the folding rolls to the delivery guide 8. The rolls 3 and 4 run ordinarily at a much higher rate of speed than the cylinder 1. Ordinarily contact 50 between the paper and the rolls 3 and 4 causes offset and sometimes wrinkles. Moreover, roll 4 runs in a direction opposite to the direction of motion of the paper before

it begins to be folded. Thus it sometimes strikes the paper off the forwarding pins, 55 particularly the outer sheet or sheets when a considerable number are folded at once. Then the edge of the incoming sheet strikes the roll 4 and goes between the rolls. It is to avoid these difficulties that this invention 60 is made.

For this purpose a pair of stationary rods 10 are mounted parallel with the folding rolls and fixed to the frame of the machine. On these rods are fixed arms 11 which extend inwardly toward the rolls and project over them. These arms preferably extend into grooves 12 in the rolls which are provided to receive the forwarding pins 6. They are provided with convex upper surfaces which have a greater radius than that of the rolls so that these surfaces extend into a position to keep the paper from contact with the rolls. These arms are shown as arranged in pairs extending 70 into each of the grooves 12. These arms thus constitute guards and a plurality of them may constitute the entire guard. However, I have shown them as supplemented by sheet metal plates 13 secured to the arms and 80 partaking of the curvature thereof. Preferably, these are used but they may be dispensed with if desired. When used they are separated at their ends over the grooves 12 to provide a space for the pins 6. The rolls 85 3 and 4 are shown as fluted.

The operation of the arrangement will be obvious. The guard located over the roll 4 is of particular importance because it prevents the incoming forward edge of the sheet 90 from bending down and striking the roll 4 and thus being forced by the rotation of the roll into the bite. With this guard in position the incoming edge will strike it if it comes along in a low position. Then it is 95 forced upwardly along it by the movement of the folding cylinder, thus restoring the paper to its proper position. Both guards also prevent off-set and wrinkling during 100 the folding operation, by preventing the folding rolls having any contact with the paper other than what is required to perform the necessary folding operation.

Although I have illustrated only one form and described only two forms of the invention and shown it as applied to a single type 105

of folding mechanism, I am aware of the fact that modifications can be made in the construction and that it can be applied to substantially all types of rotary folding rolls without departing from the scope of the invention as expressed in the claims. Therefore, I do not wish to be limited in these respects, but what I do claim is:—

1. In a folding mechanism the combination of a folding cylinder and an adjacent folding roll, sheet forwarding pins on said cylinder adapted to lead the sheet by its forward edge over said adjacent folding roll, the surface of which roll moves in a direction opposite to that of the sheet, a guard interposed between the said cylinder and said roll to prevent the leading edge of the sheet from contacting with said roll, said guard being located out of the pathway of the said pins.

2. The combination with a folding cylinder having forwarding pins and arranged to carry sheets on its surface and a pair of folding rolls located closely adjacent thereto to receive the sheets therefrom, of a guard extending over the off roll toward which the leading edge of the sheet is fed by the cylinder, said guard being arranged to permit the pins to pass through it and extending into the space between the two rolls to prevent contact of the leading edge of the sheet with said off roll.

3. The combination with a folding cylinder having forwarding pins and arranged to carry sheets on its surface and a pair of folding rolls located closely adjacent thereto to receive the sheets therefrom, of a pair of guards extending over the folding rolls and one of them being arranged to permit the pins to pass through it, the ends of said guards projecting into the space between said folding rolls to prevent contact of the leading edge of the sheet with said rolls

when the sheet passes over them before folding.

4. The combination with a folding roll of arms located in planes transverse to the axis of said roll and intersecting its cylindrical surface, and having convex guard surfaces beyond the circumference of the roll.

5. The combination with a folding roll, having circumferential grooves of arms extending into said grooves, and convex plates secured to said arms over the roll, and spaced apart at their ends.

6. The combination with a folding cylinder having forwarding pins and a folding roll, of a plurality of guard plates projecting between said cylinder and roll having spaces between them for the forwarding pins.

7. The combination with a folding cylinder having forwarding pins and a pair of folding rolls, of arms projecting over the surface of one of said rolls, and a plurality of thin plates mounted on said arms over the roll having spaces between them for the forwarding pins.

8. In a folding mechanism, the combination of a folding cylinder having forwarding pins for carrying sheets, a pair of folding rolls adapted to fold the sheets carried by the said cylinder, one of which rolls runs at its top side in a direction opposite to that of the said sheets, and a guard, interposed between the said cylinder and roll, and adapted to prevent the said roll from stripping the leading edges of the sheets from the pins during their passage over the roll.

In testimony whereof I have hereunto set my hand, in the presence of two subscribing witnesses.

HENRY A. WISE WOOD.
